UNITED STATES PATENT OFFICE.

THOMAS J. IRWIN, OF BROOKLYN, NEW YORK.

NON-REFILLABLE BOTTLE.

SPECIFICATION forming part of Letters Patent No. 761,298, dated May 31, 1904.

Application filed March 22, 1904. Serial No. 199,328. (No model.)

To all whom it may concern:

Be it known that I, THOMAS J. IRWIN, a citizen of the United States, residing at Brooklyn, in the county of Kings and State of New York, have invented certain new and useful Improvements in Non-Refillable Bottles, of which the following is a specification, such as will enable those skilled in the art to which it appertains to make and use the same.

10 This invention relates to bottles, jugs, jars, and similar vessels; and the object thereof is to provide a vessel of this class with an interior neck attachment whereby the vessel when once filled and the neck attachment applied 15 may be emptied of its contents, but cannot be refilled or reused.

In the accompanying drawings I have shown my improvement applied to an ordinary bottle, and the invention is fully disclosed in the 20 following specification, of which said drawings form a part in which the separate parts of my improvement are designated by suitable reference characters in each of the views, and in which—

25 Figure 1 is a sectional side view of the neck portion of a bottle provided with my improvement, the improvement being also shown in section and the bottle being tilted or partially inverted; Fig. 2, a similar view showing the 30 bottle in an upright position; Fig. 3, a plan view of the bottle-neck; Fig. 4, a section on the line 4 4 of Fig. 2; Fig. 5, a section on the line 5 5 of Fig. 2; Fig. 6, a section on the line 6 6 of Fig. 2; and Fig. 7, a view similar 35 to Figs. 1 and 2, but showing the neck of the bottle inverted and in an upright position and showing the position of the parts of my improvement when an attempt is made to refill the bottle by forcing liquids thereinto.

40 In the drawings forming part of this specification I have shown at *a* an ordinary bottle having a neck *a*², and in the practice of my invention I secure in the neck *a*² a tube or tubular member *b* and in the bottom portion 45 of which is secured an open conical support *c*, around which are ports or passages *c*², and which is adapted to receive a spherical body or ball *c*³.

At a predetermined distance above the sup- 50 port *c* a transverse partition-plate *d* is secured

in the tube *b* and provided at one side with a port or passage *d*², at one side of which is hinged, as shown at *d*³, a valve *d*⁴, in which is formed a small hole *d*⁵, through which passes a small rod or wire *e*, which is secured to the ball or body *c*³ and the length of which is such that when the ball or body *c*³ is in the support *c*, as shown in Figs. 1 and 7, the bottle being inverted the wire or rod *e* extends below the plate *d*. The wire or rod *e* is free 60 to slide through the hole *d*⁵ in the valve *d*⁴, and I also preferably place on said wire or rod *e* a movable washer *f*, composed of some light material, and the end of the wire or rod *e* is provided with a knob *e*², which holds said 65 washer thereon.

Above the plate *d* and at a predetermined distance therefrom and also separated a predetermined distance are two transverse baffle-plates *g* and *h*, which are also secured in 70 the tube *b*, and in the form of construction shown the top partition-plate *h* is provided with a central port or passage *h*², and the partition-plate *g* thereunder is provided with side ports or passages *g*², the object of said baffle- 75 plates being to prevent the insertion of a wire, tool, or other instrument in an attempt to interfere with the operation of the valve *d*⁴, while at the same time permitting liquids to flow out through the neck of the bottle. 80

The operation will be readily understood from the foregoing description when taken in connection with the accompanying drawings and the following statement thereof. After the bottle has been filled with the desired 85 contents the attachment-tube *b* is secured therein in any desired manner or by any preferred means and the end of the neck is closed by a cork or stopper in the usual manner. When it is desired to empty the bottle or dis- 90 charge a portion of its contents, the bottle is inverted or tilted, as shown in Fig. 1. In this operation the ball or body *c*³ drops into the support *c*, as shown in said figure, and the valve *d*⁴ drops downwardly on the wire or rod *e*, as is also shown in said figure, and the contents of the bottle will flow out through the 95 ports or passages *c*², around the support *c*, through the port or passage *d*² in the plate *d*, and through the ports or passages *g*² in 100

the plate *g* and through the port or passage *h*² in the plate *h*, and this operation may be continued or repeated until the bottle is entirely emptied.

5 If an attempt be made to refill the bottle by pouring liquids thereinto, the ball or body *c*³ will drop into the position shown in Fig. 2, and the valve *d*⁴ will be closed, as is also shown in said figure, and no liquids can enter the 10 bottle.

If an attempt be made to force liquids into the bottle by holding the bottle in an inverted or tilted position, the ball or body *c*³ will drop into its support or seat *c* and the liquids 15 which are forced into the neck of the bottle will raise the valve *d*⁴ and force it to its seat, as shown in Fig. 7, and in this operation the washer *f* will also rise on the wire or rod *e* and will aid in closing the hole *d*⁵ in the valve.

20 The hole *d*⁵ may be made so small that the valve *d*⁴ will close the neck of the bottle without the use of the washer *f*, as it will be understood that the wire or rod *e* is very small, and the hole *d*⁵ may also be made very small, 25 and no liquids could enter the bottle against the pressure of the air therein, and there would be no way for said air to escape.

My improvement is simple in construction and operation and is also comparatively inexpensive and may be applied to any kind or 30 class of vessels herein specified or other vessels similar thereto.

Having fully described my invention, what I claim as new, and desire to secure by Letters 35 Patent, is—

1. A bottle or similar vessel provided with a neck attachment which is secured therein, said attachment comprising a tube, a transverse support secured in the bottom portion 40 of the tube and having a central opening around which are ports or passages, a body,

placed in said tube and adapted when the bottle is inverted to rest in said support in said opening, a transverse valve-plate secured in said tube above said support and provided 45 with a port or passage, a valve hinged to the top of said plate and adapted to close said port or passage, a rod or wire connected with said body and passed loosely through said valve and of a length greater than the distance between said support and the valve-plate, and baffles secured in said tube above said valve-plate, substantially as shown and described.

2. A bottle or similar vessel provided with a neck attachment which is secured therein, 55 said attachment comprising a tube, a transverse support secured in the bottom portion of the tube and having a central opening around which are ports or passages, a body placed in said tube and adapted when the bottle is inverted to rest in said support in said opening, a transverse valve-plate secured in said tube above said support and provided with a port or passage, a valve hinged to the top of said plate and adapted to close said port 60 or passage, a rod or wire connected with said body and passed loosely through said valve and of a length greater than the distance between said support and the valve-plate, and baffle-plates secured in said tube above said 65 valve-plate, said wire or rod being also provided at the end thereof with a knob and with a washer which is movable thereon, substantially as shown and described.

In testimony that I claim the foregoing as 75 my invention I have signed my name, in presence of the subscribing witnesses, this 21st day of March, 1904.

THOMAS J. IRWIN.
